RING BINDER

Henry T. Adams and Norman D. Nachtrieb,
Chicago, Ill.; said Nachtrieb assignor to said
Adams

Application May 27, 1932. Serial No. 613,943

10 Claims. (Cl. 129—24)

This invention relates to ring binders and more particularly to binders employed with loose-leaf books.

An object of the invention is to provide a ring binder of improved construction and operation in which three or more rings may be supported and simultaneously operated. Other objects and advantages will appear as the specification proceeds.

10 The invention is illustrated, in a preferred embodiment in the accompanying drawing in which: Figure 1 is a top plan view of a binder embodying our invention; Fig. 2, a bottom plan view; Fig. 3, an enlarged sectional view, the section being taken as indicated at line 3 of Fig. 1; Fig. 4, an enlarged sectional view showing the half ring prongs in open position, the section being taken as indicated at line 4 of Fig. 1; Fig. 5, a broken enlarged, sectional view, the section being taken as indicated at line 5 of Fig. 1; and Fig. 6, an enlarged sectional detail view, the section being taken as indicated at line 6 of Fig. 1.

In the illustration given, 10 designates a metal back strip or casing having inwardly turned edges or sides 11 and 12. The casing is open on its bottom side which normally faces the portion of the loose-leaf book to which it may be attached. Openings 13 are provided near the ends of the back strip through which rivets or other fastening means may be passed. In order to buttress the ends of the metal back strip and to avoid raw edges of the metal, we preferably form the ends as illustrated in Figs. 1, 2 and 6. Each end is provided with a tapered or downwardly inclined concave wall 14 which terminates in a substantially straight edge 15. The edge 15 is aligned with the bottom of the side walls 11 and 12 and is adapted to rest evenly upon the loose-leaf book. The corners of the side walls 11 and 12 are cut away at the ends to provide rounded or tapering ends 16.

The top wall of the back strip 10 is provided with a number of ring member openings 17 which permit the leaf-impaling rings to extend therethrough. In the illustration given, three sets of spaced openings are shown.

The ring members are preferably formed in duplicates. In the illustration given, the ring members designated by the numeral 18 are duplicates and the members 19 are duplicates. Each of the members 18 is provided with a shank portion 20, which engages one of the side walls of the back strip, and with inwardly turned terminal arches 21. A half ring prong 22 is carried by

each of the arches and extends through an opening 17 in the back strip.

Each of the ring members 19 is also provided with a central shank 23 and at its outer end with an inwardly turned arch 24. The arch carries a 60 half ring prong 25 which extends through one of the openings 17. At its inner end, however, the member 19 is provided with an inwardly turned portion 26 equipped with an upwardly curved and tapered extension 27.

65 The ring members are preferably assembled as shown in Figs. 2 and 5. The arches 24 and inwardly turned portions 26 of the ring members 19 are provided with tongues or swaged extensions 28 which engage grooves 29, with which the arches 70 of members 18 are provided, to form toggle joints. As is shown clearly in Figs. 2 and 5, the inner ends 27 of members 19 are turned upwardly so as to 75 rest upon the inner arches 21 of members 18. In order to provide room for the play of the interlocking members, we stamp the top wall of the back strip outwardly to form a crown or recess 80 30. The crown 30 not only serves to house the interlocked ends of the ring members but also braces and strengthens the central portion of the 80 back strip and confines the interlocked members in operative relation.

85 In the operation of the device, any one of the rings may be operated so as to simultaneously open or close the other rings. In the arrangement shown, there are two pairs of oppositely disposed ring members, each pair including a member 18 and a member 19, the duplicate members 18 and the duplicate members 19 being 90 diagonally positioned within the casing with respect to each other. The two pairs of ring members have an interlocking engagement at their inner ends. Each pair has one member, the arch 21, extending under a member, extension 27, of the other pair; also, each pair has a member, 95 extension 27, extending over a member, arch 21, of the other pair. In other words, each of the pivotally connected pairs has a part extending over and a part extending under the members of the other pair. With this arrangement, when 100 one of the ring members is swung to one position, it causes a corresponding movement of its companion member and of the other pair of members. For example, if one of the rings is moved from closed position, as shown in Fig. 3, to the 105 open position shown in Fig. 4, the arch 21 of member 18 directly actuated will raise the extension 27 of the longitudinally adjacent member 19 and the member 19 will in turn actuate member 18. Likewise, in closing one of the rings, the 110

- extension 27 of the member 19 which is directly actuated will depress the contacting arch 21 of the member 18 of the other pair while, at the same time, the companion ring members in each 5 pair are actuated by reason of the pivotal connections. In swinging the rings to open position, room is provided for the superposed or interlocked ring member connections by the recess or crown 30 in casing 10.
- 10 The use of duplicates greatly reduces the number of manufacturing operations and the number of dies required. The parts employed permit ready and inexpensive assembly and, in their assembled relation, operate accurately and easily.
- 15 The foregoing detailed description has been given for clearness of understanding only, and no unnecessary limitations should be understood therefrom, but the appended claims should be construed as broadly as permissible, in view of 20 the prior art.
- We claim:
1. In a device of the character set forth, a back strip equipped with inturned edges, a plurality of longitudinally aligned ring members 25 engaging said edges, interlocking connections formed by the ends of at least two of said longitudinally aligned members, and transverse pivotal connections between ring members disposed on opposite sides of said back strip.
  2. In a device of the character set forth, a back strip equipped with inturned edges, mating pairs of oppositely disposed ring members engaging said edges, said mating pairs being in longitudinal alignment and each having inwardly turned portions provided with hinged connections, half rings carried by said ring members 35 and extending through said back strip, and interlocking connections formed by the ends of at least two of said longitudinally aligned members.
  3. In a device of the character set forth, a back strip provided with inturned edges, longitudinally aligned ring members engaging said edges, interlocking connections formed by the ends of at least two of said longitudinally aligned 45 members, said back strip being provided on its closed side with a recess extending over said interlocking connections, and transverse pivotal connections between the ring members disposed upon opposite sides of the back strip.
  4. In a device of the character set forth, a back strip casing provided with inturned edges, duplicate ring members diagonally disposed with respect to each other within said casing, interlocking connections formed by the ends of at least two of the longitudinally aligned members, and transverse pivotal connections between ring members disposed on opposite sides of the back strip casing.
  5. In a ring binder, a back strip provided on its closed side with a recess, said back strip being also provided with inturned side walls, and two pairs of oppositely disposed ring members engaging said inturned side walls, each pair being longitudinally aligned with the other pair and the diagonally disposed ring members being duplicates of each other, said longitudinally aligned pairs being provided with interlocking end portions adjacent the recess of said back strip, and the oppositely disposed members of each pair being pivotally connected.
  6. In a ring binder, a back strip provided with inturned edges and with ring openings through said back strip, a pair of diagonally opposed ring members each of which is equipped at its ends with inwardly turned arches and with half rings extending through said ring openings, a second pair of diagonally opposed ring members each having at one end an inwardly turned arch pivotally connected to the respective outer arch of said first-mentioned ring members and having at its other end an inwardly turned portion pivotally connected to an arch of said first-mentioned ring members, each of said second-mentioned ring members having also an extension passing over the inner arch of the ring member longitudinally aligned therewith, and a recess in said back strip housing said ring member extensions. 80
  7. In a ring binder, a back strip casing having inwardly turned side walls and having ring openings therein, two pairs of oppositely disposed and pivotally connected ring members engaging the side walls of said back strip casing, each of said pairs being equipped with half rings extending through said ring openings and being longitudinally aligned within said casing with respect to each other, pivotal connections between the oppositely disposed members of each pair, and end portions of said longitudinally aligned members forming interlocking connections so that movement of one ring produces a corresponding movement of the other rings. 90
  8. In a three-ring binder, a back strip equipped with inwardly turned side walls, two pairs of ring members engaging the side walls of said back strip, each pair comprising oppositely disposed and pivotally connected ring members and being longitudinally aligned with the other pair of ring members, half rings carried by said oppositely disposed members at their outer extremities and half rings carried by one of each pair of ring members at their inner extremities, interlocking connections formed by the ends of at least two of the longitudinally aligned members and a recess afforded by said back strip adjacent said interlocking connections. 100
  9. In a device of the character set forth, a back strip casing closed on one side and having inturned side walls, ring members engaging said side walls, said casing having at each end a downwardly inclined and concave wall terminating in a substantially straight and flat edge, said side walls extending at their ends to a point adjacent said straight edge and forming with said inclined wall an integral bend. 110
  10. In a device of the character set forth, a back strip casing closed on one side and having inturned side walls, said side walls terminating short of the end of the back strip casing, ring members engaging the side walls, said casing having at each end a downwardly turned concave wall terminating in a substantially flat and transversely curved flange, the said downwardly inclined wall and flange being exterior to and shielding the ends of said side walls. 120
